D37-53

EX

CO. 5,812

[DESIGN.]

GEORGE D. NAPHEYS.
Tin-Pail.

No. 5;812.

Patented April 23, 1872.

UNITED STATES PATENT OFFICE.

GEORGE D. NAPHEYS, OF PHILADELPHIA, PENNSYLVANIA, ASSIGNOR TO
GEORGE C. NAPHEYS & SON, OF SAME PLACE.

DESIGN FOR A TIN-PAIL.

Specification forming part of Design No. 5,812, dated April 23, 1872.

Specification describing a Design for Tin-Pail, invented by GEORGE D. NAPHEYS, of the city of Philadelphia and State of Pennsylvania.

The nature of my design is fully represented in the accompanying photographic illustration, to which reference is made.

A is the body of the pail, which is of the form of a frustum of an inverted cone, the diameter of the vessel being greater at the top than at the bottom. Around the pail at each end there are one or more beads, b. The sides of the pail are tapering from the upper

bead to the bottom of the pail, but straight or parallel above the upper bead to receive the flange d of the lid or cover. B is a bail or handle connected with the ears e e.

I do not claim broadly an inverted conical-ribbed or beaded pail.

What I claim as my invention is—

The design for a tin-pail, as described and represented.

GEORGE D. NAPHEYS.
